[57] ABSTRACT

A partition type closure for use intermediate the opposite ends of a walled load bed or the like for dividing the interior of the walled load bed into longitudinally spaced sections. Hinge structure is provided for pivotally securing one upstanding marginal edge portion of the partition to a corresponding side wall of the load bed for swinging of the partition about an upstanding axis between a position generally paralleling the one side wall of the load bed and a position extending between the opposite side walls of the load

bed. A latch structure is provided for the other wall of the load bed and comprises an upstanding member oscillatably supported from the other side wall for angular displacement about an upstanding axis and including a plurality of parallel horizontally outwardly projecting keeper arms. The keeper arms are oscillatable, with the upstanding member, between retracted positions closely paralleling the other side wall of the enclosure and positions with the free ends of the keeper arms slightly inclined toward the side wall from which the partition is swingably supported and with the free ends of the keeper arms extending generally in the direction in which the free swinging upstanding edge of the partition is swung in order to position the partition in an operative manner extending between the side walls. Also, the other side wall from which the upstanding member is oscillatably supported includes inwardly projecting abutment members in horizontal registry with but spaced slightly along the side wall from the free ends of the keeper arms. The free swinging edge of the partition includes vertically spaced outwardly projecting cam members which are engageable with the free end portions of the keeper arms in order to cam the latter toward positions paralleling the corresponding side wall as the partition is swung to the operative position and also engageable with the abutment members after moving past the free ends of the keeper arms, there being provided spring structure for yieldingly urging the upstanding member to an angularly displaced position with the free ends of the keeper arms inclined away from the corresponding side wall so as to be engageable behind the cam members when the latter are engaged with the abutment members to thereby preclude swinging movement of the partition from the operative position extending between the side walls to an inoperative position paralleling the side wall from which the partition is oscillatably supported.

DOOR LATCH CONSTRUCTION

The door latch construction of the instant invention may be utilized in numerous environments, but is primarily designed for use in defining a swinging partition in a walled stock trailer body with the partition readily securable in a transverse partition-defining position against movement to the inoperative position and with the partition defining an effective brace between the side walls of the body.

In addition to being capable of defining a partition in a stock trailer body, the swingable gate-type partition of the instant invention may also be utilized in other environments such as a partition between loads in a vehicle body used for carrying freight. Further, it will be apparent from the following detailed description of the partition and latch construction that the invention may be used to advantage in other similar environments.

The main object of this invention is to provide a partition for use in a stock trailer that may be readily moved into an out of partition-defining position extending between the side walls of the trailer body and which will be shiftable to a retracted position closely paralleling one of the side walls of the trailer body.

Another object of this invention is to provide a latch construction for the partition whereby the latter may be automatically releasably locked in the operative position defining a partition between load bed side walls.

Another important object of this invention is to provide a latch construction in accordance with the preceding object which may be readily released.

A still further object of this invention is to provide a latch construction in accordance with the two preceding objects and which will coact with the associated partition in a manner to define a brace between the associated body side walls when the partition is releasably locked in its operative position.

A final object of this invention to be specifically enumerated herein is to provide a construction in accordance with the preceding objects which will conform to conventional forms of manufacturing, be of simple construction and easy to use so as to provide a device that will be economically feasible, long lasting and relatively trouble free in operation.

These together with other objects and advantages which will become subsequently apparent reside in the details of construction and operation as more fully hereinafter described and claimed, reference being had to the accompanying drawings forming a part hereof, wherein like numerals refer to like parts throughout.

FIG. 1 is a fragmentary perspective view of the interior of a stock trailer with the free swinging edge portion of the partition of the instant invention locked against angular displacement from the operative position by means of the latch construction portion of the instant invention;

FIG. 2 is a fragmentary top plan view of the stock trailer with the partition illustrated as releasably locked in the operative position and an alternate position of the partition illustrated in phantom lines;

FIG. 3 is an enlarged fragmentary transverse vertical sectional view taken substantially upon a plane designated by the section line 3—3 of FIG. 2;

FIG. 4 is a fragmentary enlarged side elevational view of the inner side of the wall of the trailer body from

which the latch construction is supported and with portions of the free swinging edge portion of the associated partition broken away and illustrated in vertical section;

5 FIG. 5 is a fragmentary vertical sectional view taken substantially upon the plane indicated by the section line 5—5 of FIG. 4;

10 FIG. 6 is an enlarged fragmentary horizontal sectional view taken substantially upon the plane indicated by the section line 6—6 of FIG. 4; and

15 FIG. 7 is an enlarged fragmentary horizontal sectional view taken substantially upon the plane indicated by the section line 7—7 of FIG. 4.

20 Referring now more specifically to the drawings, the 15 numeral 10 generally designates a conventional form of stock trailer including a pair of upstanding opposite side walls 12 and 14 interconnected at their lower ends by means of a bottom wall 16. A partition is referred to in general by the reference numeral 18 and comprises a pair of opposite side upstanding members 20 and 22 interconnected by means of upper and lower horizontal members 24 and 26 as well as vertically spaced intermediate horizontal members 28, 30 and 32.

25 The upstanding member 22 is pivotally supported from the side wall 14 by means of any suitable hinge assemblies 34 and the free swinging edge portion of the partition 18 includes endwise horizontally outwardly projecting cam members 36 and 38. The cam member 30 36 is supported from the upper end of the upstanding member 20 and includes a horizontal flange 40 which projects outwardly beyond the upstanding member 20 and terminates at its outer end in a right angularly directed horizontal flange 42 projecting from the flange 35 40 in a direction in which the partition 18 is swung from a retracted position paralleling the side wall 14 to an operative position extending between the side walls 12 and 14.

30 A short length of chain 44 is secured to the free 40 swinging end portion of the upper horizontal member 24 and the free end of the chain 44 is engageable over an upstanding pin 46 projecting upwardly from the upper marginal portion of the side wall 14 in order to 45 secure the partition 18 in a retracted position closely paralleling the side wall 14.

50 From FIGS. 1 and 4 of the drawings it may be seen that a pair of upper and lower mounting plates 48 and 50 are secured to the inner surface of the side wall 12 by means of suitable fasteners 52. The mounting plate 48 includes an upstanding reinforcing plate 54 secured to its inner surface in any convenient manner such as by welding and a pair of horizontally disposed L-shaped clips 56 and 58 are secured to the upper and lower ends of the reinforcing plate 54. The clips define aligned 55 passages 60 which are generally triangular in cross-sectional shape. Also, the mounting plate 50 has a reinforcing plate 62 secured to its inner surface by welding and a pair of upper and lower L-shaped clips 64 and 66 are secured to the reinforcing plate 62 and define vertically aligned upstanding passages 68 which are also triangular in cross-sectional shape and are aligned with the vertically extending passages 60.

60 An operating bar 70 of rectangular cross-sectional shape is received through the passages 68 and the bar 65 70 includes horizontally outwardly projecting upper and lower parallel keeper arms 72 and 74. The upper arm 72 projects outwardly from that portion of the bar

70 disposed between the clips 56 and 58 and the arm 74 projects outwardly from the portion of the bar 70 disposed between the clips 64 and 66, the undersurface of the base end of the arm 74 bearing upon the opposing upper surface of the clip 66 in order to support the bar 70 against downward displacement relative to the clips 56, 58, 64 and 66. The upper end of the bar 70 includes a horizontally outwardly directed terminal portion 76 and the free end of the terminal portion 76 is provided with a horizontally disposed operating handle 78. Also, an expansion spring 80 is secured between the operating handle 78 and one of the fasteners 52 securing the mounting plate 48 to the side wall 12. The expansion spring 80 serves to yieldingly bias the bar 70 to an angularly displaced position such as that illustrated in FIGS. 6 and 7 of the drawings.

A lower abutment member 84 is secured to the mounting plate 50 and is spaced slightly outwardly of and opposes the free end of the keeper arm 74. Also, the mounting plate 48 includes a pair of vertically spaced horizontal and inwardly projecting guide plates 86 between which the free swinging end of the keeper arm 72 is received and the ends of the guide plates 86 adjacent the bar 70 diverge slightly toward the bar 70.

An abutment member in the form of an upstanding flange 90 is secured between the plates 86 a spaced distance inwardly from the mounting plate 48 and a similar upstanding flange defining a wear plate 92 is also secured between the plates 86 between the abutment 90 and the mounting plate 48. The upstanding edge of the wear plate 92 adjacent the keeper arm 72 is rounded as at 94 and the horizontal spacing between the abutment 90 and the wear plate 92 is such to receive the flange 42 of the cam member 36 between the wear plate 92 and the abutment 90 when the partition 18 is in the operative position.

In operation, the handle 78 may be operated to angularly displace the bar 70 from the position thereof illustrated in FIGS. 6 and 7 of the drawings so as to swing the keeper arms 72 and 74 from the solid line positions illustrated in FIGS. 6 and 7 to the inactive retracted positions illustrated by phantom lines in FIGS. 6 and 7. Thereafter, the partition 18 may be readily swung from the operative position illustrated in solid lines in FIG. 2 of the drawings in the direction of the arrows 96 in FIG. 2 so as to swing the partition 18 toward a position closely paralleling the inner surface of the side wall 14. After the partition 18 has been swung to the fully retracted position, the free end of the chain 44 may be engaged with the upstanding pin 46 so as to retain the partition 18 in the retracted position.

On the other hand, when it is desired to swing the partition 18 to the operative position, it is merely necessary to disengage the chain 44 from the pin 46 and to swing the partition 18 toward the side wall 12. As the partition 18 approaches its operative position, the flange 42 of the cam member 36 will engage the keeper arm 72 and the abutment 38 will engage the keeper arm 74 so as to swing the arms 72 and 74 to the retracted phantom line positions thereof illustrated in FIGS. 6 and 7 thereby enabling the flange 42 and the abutment 38 to swing past the free ends of the keeper arms 72 and 74. As soon as the flange 42 and the abutment 38 have swung past the free ends of the arms 72 and 74, the flange 42 of the cam member 36 and the cam member 38 will engage the flange or abutment

member 90 and the abutment member 84 to limit swinging of the partition 18 to the operative position. However, as soon as the cam members 36 and 38 swing past the free ends of the arms 72 and 74, the spring 80 is operative to angularly displace the bar 70 so as to swing the free ends of the arms 72 and 74 behind the flange 40 and the abutment 38 thereby retaining the flange 40 and the abutment 38 captive between the arms 72 and 74 and the abutments 90 and 84. Of course, inasmuch as the flange 42 is received between the wear plate 92 and the abutment 90, lateral displacement of the wall 12 relative to the wall 14 is limited and thus the partition 18 also defines a brace extending between the walls 12 and 14 when the partition 18 is in its operative position.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention.

What is claimed as new is as follows:

- 25 1. In combination with a pair of opposed spaced upright support members, a gate member, means securing one marginal edge portion of said gate member to one of said support members for swinging of the opposite marginal edge portion of said gate member toward and away from the other support member about a first upright axis, an elongated rigid strap-type bar member, at least two pairs of slightly vertically spaced L-shaped mounting clips secured to and spaced vertically apart along said other support member in an upstanding path of alignment generally paralleling said first axis, said L-shaped mounting clips being horizontally disposed and having the free ends of the leg portions thereof opposing and secured to said other support member and the apex portions thereof defined at the juncture of said leg portions opposing said one support member, said clips together defining an upstanding passageway of a cross-sectional shape including a first pair of opposite short sides and a second pair of opposite longer sides with said lower sides being slightly convergent toward one of the short sides, said bar being of a thickness slightly less than the length of said one short side and of a width slightly less than the length of said longer sides and extending through said clips and received therethrough for limited oscillation about a second axis extending along the edge portion of said bar disposed between the convergent ends of said longer sides, longitudinally spaced portions of said elongated bar including a pair of laterally outwardly projecting keeper arms, each of said arms projecting outwardly from said bar between one pair of said clips and being swingable, during angular displacement of said elongated bar between its limit positions, between retracted positions generally normal to said gate member when the latter is in the closed position extending between said support members and operative positions with the free ends of said arms swung at least slightly toward said one support member, abutment members carried by said other support member and spaced slightly outwardly of the free ends of said arms, the free swinging edge portion of said gate member including cam members registrable and engageable with at least the free ends of said arms to cam said arms toward their retracted positions,

means yieldingly biasing said bar to the limit position thereof with said arms in said operative positions, said cam members being swingable past the free ends of said arms when the latter are in the retracted positions and engageable with said abutment members between the latter and the ends of said arms for retaining said gate member in the closed position thereof when said arms are in their operative positions, the lower surface of at least one of said arms being disposed in sliding contacting relation with the upper edges of the clip disposed therebetween for limiting downward shifting of said elongated bar relative to said other support member.

2. The combination of claim 1 wherein said support members comprise upstanding opposing walls of a load receptacle.

3. The combination of claim 2 wherein the side wall comprising said one support member includes an anchor member, the free swinging end portion of said

gate member including an anchor element releasably engageable with said anchor member when said gate is swung into position generally paralleling the last mentioned side wall.

5 4. The combination of claim 1 wherein one of said abutment members comprises a flange portion supported in outstanding relation therefrom toward said one support member and with said flange disposed generally normal to said gate member when the latter is in its closed position, said gate member including a keeper flange outstanding from the free edge portion of said gate member and swingably receivable between said flange portion and said other support member during final swinging of said gate member to said closed position thereof with the other cam members abutted against said abutment members.
